UNITED STATES PATENT OFFICE.

CLARENCE A. PETERSON, OF WASHINGTON, DISTRICT OF COLUMBIA, ASSIGNOR TO
WELSBACH LIGHT COMPANY, OF GLOUCESTER CITY, NEW JERSEY, A CORPORATION
OF NEW JERSEY.

DESIGN FOR AN INVERTED GAS-BURNER.

43,677.

Specification for Design.

Patented Mar. 4, 1913.

Application filed November 19, 1912. Serial No. 732,370. Term of patent 14 years.

To all whom it may concern:

Be it known that I, CLARENCE A. PETERSON, a citizen of the United States, residing at Washington, in the District of Columbia, have invented a new, original, and ornamental Design for Inverted Gas-Burners, of which the following is a specification, reference being had to the accompanying drawing, forming part thereof.

The figure is a perspective view of an inverted gas burner embodying my design.

I claim:

The ornamental design for an inverted gas burner, as shown.

In testimony whereof, I have hereunto set my hand.

CLARENCE A. PETERSON.

Witnesses:

JAMES H. VAWTER,
WM. D. COLT.
